UNITED STATES PATENT OFFICE

ROBERT J. HILL, OF CRANSTON, RHODE ISLAND, ASSIGNOR TO THE TRAVELERS INSURANCE COMPANY, OF HARTFORD, CONNECTICUT, A CORPORATION OF CONNECTICUT

DESIGN FOR A BOOK END

Application filed March 13, 1931. Serial No. 39,074. Term of patent 14 years.

To all whom it may concern:

Be it known that I, ROBERT J. HILL, a citizen of the United States, and a resident of Cranston, in the county of Providence and State of Rhode Island, have invented a new, original, and ornamental Design for Book Ends, of which the following is a specification, reference being had to the accompanying drawings, forming part thereof, in which—

I claim:

The ornamental design for a book end, as shown.

ROBERT J. HILL.
